S. H. APPELMAN,
CALK ATTACHMENT FOR CRUTCHES.
APPLICATION FILED MAY 20, 1913.

1,090,960.

Patented Mar. 24, 1914

UNITED STATES PATENT OFFICE.

SAMUEL H. APPELMAN, OF BLOOMSBURG, PENNSYLVANIA.

CALK ATTACHMENT FOR CRUTCHES.

1,090,960.

Specification of Letters Patent. Patented Mar. 24, 1914.

Application filed May 20, 1913. Serial No. 768,893.

To all whom it may concern:

Be it known that I, SAMUEL H. APPELMAN, citizen of the United States, residing at Bloomsburg, in the county of Columbia 5 and State of Pennsylvania, have invented certain new and useful Improvements in Calk Attachments for Crutches, of which the following is a specification.

My invention relates to new and useful 10 improvements in crutches of the type in which the crutch is provided with a sharp steel point or calk which can be readily extended beyond or withdrawn into the lower end of the crutch without removing the 15 crutch from beneath the arm.

The primary object of my invention is to provide a novel form of latch for normally holding the rod in withdrawn position frictionally and so arranged that it will automatically lock the calk in extended position 20 when the latter is moved outwardly, the automatic locking of the latch serving to limit the outward movement of the calk.

With these and other objects in view, my 25 invention will be more fully described, illustrated in the accompanying drawing, and then specifically pointed out in the claims which are attached to and form a part of this application.

30 In the drawings: Figure 1 is a perspective view of my improved crutch; Fig. 2 is a fragmentary, longitudinal sectional view, showing certain details of its construction; Fig. 3 is a fragmentary longitudinal sectional view of the staff portion of my crutch 35 showing still further details of construction; Fig. 4 is a transverse sectional view taken on the line 4—4 of Fig. 2, looking upwardly.

Corresponding and like parts are referred to in the following description and indicated in all the views of the drawing by 40 the same reference characters.

My invention may be applied to or embodied in the construction of crutches of all 45 types but for the sake of clearness I have shown the same applied to a conventional form of crutch including the spaced side members 10 and 11, the lower ends of which are brought together to form a common staff 50 12 and the upper ends of which are connected and held in proper spaced relation by a cross bar forming a shoulder rest 13. The intermediate portions of the side bars 10 and 11 are connected by a handle 14 55 which also serves to brace and stiffen the side members and maintain them in spaced

relation. The lower end of the staff 12 of the crutch is bound by a ferrule 15 to prevent splintering and the upper end of the staff adjacent the point of merger of the 60 sides 10 and 11 is bound with a second ferrule 16. These ferrules are preferably formed of brass, although any other suitable metal or material may be employed instead. 65

The staff is provided centrally throughout its length with a longitudinally extending bore 17 and fitting within this bore is a ferrule 18 also preferably formed of brass. This ferrule may extend throughout practically the entire length of the staff portion of the crutch or may terminate slightly above the lower end thereof, its function being to form a bearing for the operating rod or spur rod 19 which carries the calk 20. This bushing or sleeve 18 not only forms a bearing for the spur rod but its lower portion prevents binding of the spur rod in the bore through swelling of the crutch during damp weather. The lower end of the spur rod 19 80 is provided with a threaded socket to receive the reduced, threaded stud 21 of the calk 20, the body portion of the calk being cylindrical in shape and terminating at its lower end in a conical point 22. Both the 85 spur rod and calk are preferably formed of steel and the former should be reasonably resilient, while the latter may be made harder and more highly tempered to insure satisfactory wearing qualities. 90

A U-shaped bracket 23, also preferably formed of steel, is secured by screws 24 between the side portions 10 and 11 of the crutch at a point slightly below the handle 14, the side portions of said bracket being 95 directed downwardly along the inner faces of said members. This bracket is provided at a point slightly in advance or at the rear of the center with a bore 25 equal in diameter to the diameter of the spur rod 19 100 and said rod is extended upwardly through the bore, terminating at its upper end in a knob or handle 26, preferably formed integrally with the rod. A slot 27 is formed in the bracket, extending longitudinally 105 thereof and communicating at one end with the bore 25 and ending at its opposite end centrally of the bracket, this slot being slightly less in width than the diameter of the bore. The spur rod 19 is provided at 110 a point slightly below its handle 26 with an encircling channel or groove 28 equal in di-

ameter to the width of the slot 27 and providing squared spaced shoulders.

A bearing plate 29 of steel is brazed or otherwise secured to the lower face of the bracket 5 at that side adjacent the bore 25 and has its inner end cut-away arcuately as shown at 30 to conform to the adjacent portion of the bore 25 with which it is in alinement. This plate, together with the bracket, 10 forms a bearing surface for the spur rod during its movement to advance or retract the calk 20.

An angular leaf spring 31 is secured by one arm to the lower face of the bearing 15 plate 29 by a screw 32 which passes through said spring arm, through the bearing plate and partially through the bracket 23. The spring is further secured in place and held 20 against all pivotal movement about the screw by extending one reduced end 33 into a recess 34 formed in the adjacent side portion of the bracket 23. The opposite arm of this spring extends inwardly and downwardly engaging against the spur rod to 25 constantly tend to force the same into the slot 27. In operation, assuming that the parts are in the position shown in full lines in Fig. 2 of the drawing, it will be apparent that the spring 31, pressing against the spur 30 rod 19 as it does, forces the same into frictional engagement with the adjacent opening of the slot 27 and so holds the rod frictionally against movement. Moreover, inasmuch as the bore 25, through which the rod 35 at this time extends, is formed slightly away from the center of the bracket and consequently slightly out of vertical alinement with the bore 17 through which the lower portion of the rod extends the resiliency of 40 the rod itself will further act to lock the same in place. In this position, the lower end of the spur rod, together with the calk carried thereby is retracted into the lower end of the staff portion of the crutch and the 45 crutch may therefore be used upon polished floors or other surfaces without danger of marring the same because of the calk.

Whenever the person using the crutch encounters an icy or otherwise slippery surface 50 he may however, extend the calk merely by pressing downwardly upon the knob or handle 26 at the upper end of the spur rod to force the same against the frictional engagement between said rod and the end of 55 the slot until the reduced portion 25 reaches the plane of the bracket 23 when both the resiliency of the spur rod and the pressure of the spring 31 will act to seat the reduced portion of the spur rod in the farther end 60 of the slot 27. When so seated the shoulders resultant from forming of the groove or channel 28 in the spur rod will engage one above and one below the bracket 23 and absolutely lock the spur rod against either up- 65 ward or downward movement. It will of

course be understood that the spur rod is so proportioned that in this position the calk is extended a suitable distance below the lower end of the crutch staff. The calk may at any time be again retracted by swinging the upper end of the spur rod against the action of the spring 31 until the spur rod is seated in the bore 25 and by then pulling upwardly upon the rod to retract the calk.

It will of course be apparent that this invention may be applied either to crutches having plain wooden terminals or crutches having the ordinary cup-shaped rubber tips one of which is conventionally shown at 35. In this latter case, of course, the tip will be 80 provided with a bore 36 in alinement with the bore of the crutch staff.

Although I have fully described my invention in all its details, it will be understood that I do not intend in any way to 85 limit myself to the specific details of construction illustrated in the drawing and described in the foregoing specification, as various minor changes, within the scope of the appended claims may be made at any 90 time without in the slightest degree departing from the spirit of my invention.

Having thus described the invention, what is claimed as new is:

1. In a crutch having spaced side members connected intermediate their length by a handle and merging at their lower ends into a staff portion having a longitudinal bore, a bracket extending between the side members and provided with a bore and a longitudinal slot communicating with the bore and less in width than the diameter of the bore, the bore being offset vertically with respect to the bore of the staff and the remote end of the slot being in vertical alinement 95 with the bore of the staff, a resilient operating rod carrying a calk at its lower end 100 slideable through the bore of the bracket and staff to extend or retract the calk below the lower end of the staff, said operating rod being provided with a reduced portion to permit the seating of the rod in the slot through the resiliency of the rod when the rod is lowered to extend the calk, and additional means for forcing the rod into the slot. 105

2. In a crutch having spaced side members connected intermediate their length by a handle and merging at their lower ends into a staff portion having a longitudinal bore, a bracket extending between the side members and provided with a bore and a longitudinal slot communicating with the bore and less in width than the diameter of the bore, the bore being offset vertically with respect to the bore of the staff and the remote 110 end of the slot being in vertical alinement with the bore of the staff, a resilient operating rod carrying a calk at its lower end 115 slideable through the bore of the bracket and staff to extend or retract the calk below the 120

125

130

lower end of the staff, said operating rod being provided with a reduced portion to permit the seating of the rod in the slot through the resiliency of the rod when the rod is lowered to extend the calk, and additional means for forcing the rod into the slot, said means including an angular leaf spring secured by one arm to the lower face of the bracket and having a reduced end

seating in a socket formed in the bracket, the 10 opposite arm of said spring bearing against the rod.

In testimony whereof I affix my signature in presence of two witnesses.

SAMUEL H. APPELMAN. [L. S.]
